UNITED STATES PATENT OFFICE.

WILLIAM AUGUST ROOS, OF NEW YORK, N. Y.

FOOT SCRAPER AND CLEANER FOR AUTOMOBILE RUNNING-BOARDS.

1,212,111.

Specification of Letters Patent.

Patented Jan. 9, 1917.

Application filed March 22, 1916. Serial No. 85,894.

To all whom it may concern:

Be it known that I, WILLIAM A. Roos, a citizen of the United States, and a resident of the city of New York, borough of

5 Manhattan, in the county and State of New York, have invented a new and Improved Foot Scraper and Cleaner for Automobile Running-Boards, of which the following is a full, clear, and exact description.

10 This invention relates to foot cleaning devices especially adapted for automobile running-boards, whereby the tracking of dirt into the car can be avoided by the use of the device.

15 The invention has for its general objects to improve and simplify the construction of foot cleaning devices of the character referred to, so as to be reliable and efficient in use, comparatively simple and inexpensive to manufacture, and so designed that it can be used as an attachment for cars already in use, or can be built into the car body.

20 A more specific object of the invention is the provision of a combined brush and scraper hingedly mounted on or adjacent the running-board, so that when it is desired for use it can be dropped down to horizontal position on top of the running-30 board, so that the shoes can be scraped and cleaned before stepping into the car, and when the device is no longer used it is thrown up to vertical position, close to the car body, or into a pocket therein, so as to be out of the way.

25 With such objects in view, and other which will appear as the description proceeds, the invention comprises various novel features of construction and arrangement of 40 parts which will be set forth with particularity in the following description and claims appended hereto.

30 In the accompanying drawing which illustrates one embodiment of the invention and 45 wherein similar characters of reference indicate corresponding parts in all the views, Figure 1 is a perspective view of a portion of an automobile, showing the cleaning device in position for use on the running-board; Fig. 2 is a sectional view of the running-board and adjacent part of the car body with the cleaning device shown in operative position by full lines and inoperative position by dotted lines, the car body 50 being modified to receive the device when not in use; Fig. 3 is a sectional view on the

line 3—3, Fig. 2, showing the cleaning device in plan; and Fig. 4 is an upper sectional view on the line 4—4, Fig. 2, when the brush is not in use.

60 Referring to the drawing, 1 designates the running-board of an automobile, to which is applied the foot cleaning device A. This device comprises a brush 2 and a scraper 3 and combined brackets and locks 4 which fasten the brush and scraper to the running-board 1. The brush comprises a back 5 and suitable bristles 6, and fastened to the sides of the back is a metal frame composed of side members 7 and a cross member 8. This cross member is spaced somewhat from the adjacent edge of the brush so that the member 8 can be used as a scraper. The back 5 is reinforced by a metal plate 9 which has two of its opposite edges bent into flanges 10 that interlock with the back 5. Extending across the brush and lying under the flanges are rods 11 and 12 which pass through the side members 7 of the reinforcing marginal frame. The rod 12 is in the form of a bolt, the ends of which pass through the brackets 4 to pivotally mount the combined brush and scraper on the running board. The brackets are fastened to the running-board in upstanding position and located close to the body B of the automobile, so that when the cleaning device is not in use it can occupy a vertical position close to the body.

65 If desired, the body may have a pocket b, as shown in Fig. 2, for accommodating the cleaning device. Preferably the scraping bar 8 extends outwardly beyond the edge of the running-board to permit the scrapings to readily drop clear of the latter, and also to enable the bar 8 to be easily engaged by the hand or foot for throwing the cleaning device upright to inoperative position after being used. As shown in Fig. 4, the brackets have upward extensions 4' which form 70 springs, and each spring has a lug 4" adapted to engage in an opening or depression 4" in the brush, so that the brackets form yielding locks for retaining the cleaning device in upright position.

75 From the foregoing description taken in connection with the accompanying drawing, the advantages of the construction and method of operation will be readily understood by those skilled in the art to which the invention appertains, and while I have 80 described the principle of operation to-

gether with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

- 10 1. The combination of an automobile body having a pocket in its side, a running-board under the pocket, and a foot cleaner mounted to swing in and out of the pocket and to rest on the running-board when in operative position.
- 15 2. The combination of an automobile running-board, with a foot cleaner movably mounted on the running board to rest thereon when in use and foldable to position close to the body when not in use, said cleaning device comprising a brush, and a scraper fastened to the brush and adapted to extend beyond the outer edge of the running-board.
- 20 3. The combination of an automobile body having a pocket in its side, a running-board under the pocket, and a foot cleaner mounted to swing in and out of the pocket and to rest on the running-board when in operative position, said cleaner including a brush, and a scraper arranged on the brush in such a position that it will lie beyond the edge of the running-board, whereby the scrapings will drop between the scraper and running board.
- 25 4. The combination of an automobile running-board, hinge brackets fastened to the running-board adjacent the body of the automobile, the brackets having upwardly ex-

tending spring locking members, a cleaning device pivoted on the brackets to swing outwardly from a vertical to horizontal position, and means on the members and cleaning device adapted to interlock when the latter is in upright position.

5. The combination of a vehicle body including a running-board or step, a foot cleaning device hingedly mounted to normally lie in an upright position close to the body and movable to an approximately horizontal position where the device rests on the running-board or step, said device including a brush, and a scraping bar mounted on the brush and adapted to extend beyond the outer edge of the running-board or step when the cleaning device is in use.

6. A cleaning device of the class described comprising a brush back having bristles, a frame fastened to two opposite edges of the back and having a connecting bar portion spaced from another edge of the back to form a foot scraper, a plate covering one face of the back, and the edges of the plate being bent into flanges embracing the edges of the back other than those to which the frame is applied, rods passing through the frame and under the flanges to fasten the back to the frame, and hinge brackets through which one of the bars extends to form a pivot.

In testimony whereof I have signed my name to this specification in the presence of two subscribing witnesses.

WILLIAM AUGUST ROOS.
